UNITED STATES PATENT OFFICE.

LEOPOLDO FIORILLO, OF NICE, FRANCE.

APPARATUS FOR RAISING SUNKEN SHIPS.

Application filed July 21, 1923. Serial No. 653,039.

To all whom it may concern:

Be it known that I, LEOPOLDO FIORILLO, a subject of the King of Italy, residing at Nice, France, have invented new and useful

5 Improvements in Apparatus for Raising Sunken Ships, of which the following is a specification.

This invention relates to salvage apparatus and has for its object the provision 10 of novel means for indicating the location of a sunken ship and means for effecting raising, the invention being capable of application to ships or vessels of all types and sizes.

15 An important object is the provision of an apparatus of this character including buoys which are carried by the ship and which will rise to the surface of the water in case the ship sinks, one embodiment 20 having such an arrangement that the buoys will be automatically released when the ship is submerged and another embodiment having means for effecting manual release of the buoy, the latter variation being particu- 25 larly designed for use upon submarines.

Yet another object is the provision of a form of buoy carrying normally inactive but automatically released aerial masts which facilitate the sending out of radio 30 messages and appeals for assistance.

Another object is the provision of a form of buoy equipped with hand-holds whereby quite a large number of survivors of a marine disaster may support themselves in comparative safety pending the arrival of help.

A still further object is the provision of means mounted on the vessel and connected with the float whereby a hoisting grapple may be lowered from a rescuing vessel and 40 guided to a co-acting holding device on the submerged ship so that lifting power may be applied for effecting raising.

The invention also contemplates the provision of various detailed features of construction and arrangement of the several parts which cooperate to constitute an apparatus or mechanism which will be extremely efficient and positive in action, durable in service, and a general improvement in the 45 art.

With the above and other objects and advantages in view, the invention consists in the combination and arrangement of parts to be hereinafter more fully described 50 and claimed and illustrated in the accompanying drawings in which:

Figure 1 is a sectional view through one of the units of my invention showing the form adapted to be built into the hull of a ship such as a submarine. 60

Figure 2 is a vertical section at right angles to Figure 1.

Figure 3 is a detail cross section on the line 3—3 of Figure 1.

Figure 4 is a longitudinal section on a 65 larger scale through the extensible aerial mast.

Figure 5 is a view illustrating the action when the submarine is sunk and the buoys released. 70

Figure 6 is a similar view showing a res- 75 cuing ship as lowering the hoisting grapples.

Figure 7 is a detail section on the same plane as Figure 1, showing the engagement of the hoisting grapple with the catch de- 75 vice.

Figure 8 is a detail side view of the hoisting grapple.

Figure 9 is an edge view thereof partly 80 in section.

Figure 10 is a side elevation partly in section showing the form of device used for installation upon ships other than sub- 85 marines, this view being taken substantially along the line 10—10 of Figure 11.

Figure 11 is a cross section taken substan- 90 tially along the line 11—11 of Figure 10.

Figure 12 is a plan view of the reel mechanism and associated parts.

Figure 13 is a view showing a sunken sur- 95 face vessel equipped with my device, the buoys being in their released and operative positions.

Referring more particularly to the draw- 100 ings, it will be observed that I have con- 95 structed the device for application upon and to be built into submarines and have constructed it as an attachment to be mounted upon the deck or other convenient portion of a ship of the surface type.

In applying the invention to a submersible, I form the hull A of the ship with a pocket or chamber 15 which is open-topped and which may be of any preferred specific design and of any shape and size found most advantageous for installation and reception therein of the mechanism and float to be described. Suitably secured within the bottom of this pocket or chamber is a 105 supporting frame 16 within which is journaled a grooved guide roller 17 in spaced relation to which is located a second grooved 110

roller 18. Also secured in the pocket or chamber is a bracket structure 19 in which is journaled a reel or drum 20 to which is secured and upon which is wound a cable 5 or other flexible member 21 which is doubled with its bight portion secured to the drum and its ends engaging under the rollers 17 and 18 and secured to the float or buoy 22, as shown at 23.

10 This float or buoy is of a hermetically sealed tank-like nature and fits within the upper portion of the pocket or chamber 15, the upper edge 24 being extended outwardly to a slight extent, as shown, and resting 15 upon the hull at the edge of the pocket. This float is of metal and necessarily hollow and it is preferable that it be suitably braced such for instance as by the angle irons 25 which are located therewithin at 20 different points for providing the necessary stiffness.

For normally holding the float within its retaining chamber, I provide catch devices which include vertical shafts 26 journaled in recesses 27 at the sides of the chamber and carrying heads 28 which engage over the outwardly extending edge 24 of the float. Where these shafts pass through the bottoms of the recesses and 30 naturally the hull, I provide packing glands 29 whereby to exclude any water which might tend to leak through. The number of catch devices may of course be varied to suit different conditions though in the present instance I have illustrated 4, two of 35 which have their operating shafts carrying manually operable levers 30 and the other two of which carry arms 31 with which are connected cables or other flexible members 32 which are trained over guide rollers 33, 34 and 35 located at proper points, the lower ends of both flexible members being 40 brought together and connected with a common pull cable 36 which extends down into the hull at any desired point within convenient reach of the operator. It is of course obvious that, if preferred, the flexible cables might be arranged to operate all of 45 the catches and on the other hand it is 50 equally true that all of the catches might be equipped with manually operating levers, variations in this detail being immaterial.

Pivoted at 37 upon the top of the float, is an aerial mast designated broadly by the numeral 38 and formed of telescopic sections 39, 40 and 41 normally urged into extended position by springs 42 and 43 but held in retracted position and 55 against the edge of the float by engagement 60 of the free end of the section 41 with a hook 44 on one of the catches 28. It is necessary to provide some means which will tend to throw this aerial or mast into vertical 65 position when the hook 44 is released and a convenient method of accomplishing this is

to provide a spring 45 associated with the pivot and having one arm 46 connected with the base or butt of the section 42 and its other arm connected with the bracket 47 upon which the nested mast structure is 70 pivoted. Connected with this mast by any preferred means is a radio receiving apparatus, indicated at 48, mounted within the float and having lead wires connected with a flexible conductor 49 secured to and 75 wrapped upon a reel 50 journaled in the chamber at a point opposite the reel 20. No attempt is made to show a diagram of the radio apparatus as such may be of any ordinary or preferred type. The free end of 80 this conductor should extend through the pocket into the interior of the hull at some suitable point and where this conductor passes through the wall of the float I provide a packing gland 51 to prevent leakage 85 of water.

Suitably secured within the frame 16 is a curved guide 52 spaced from the periphery of the grooved roller 17, the space having a flaring entrance 53. Pivoted within this 90 frame immediately below the roller 17, as shown at 54, is a pawl having an active arm 55 operating through an opening 56 in the guide 52. This pawl further includes a handle end 57 with which is connected a coil 95 spring 58 which is in turn suitably anchored in the chamber or pocket 15 and which operates to urge the active end of the pawl toward the periphery of the roller 17. The purpose of this pawl device is to provide 100 means whereby a grappling device lowered by a rescuing ship may be properly engaged with the hull or mechanism therein for effecting lifting of the sunken submarine.

The grappling device intended to be used 105 in connection with this catch includes a shank 59 carried by a chain 60 of suitable length or by a cable or wire chain, if cable is not available. Pivoted at 61 between the U-shaped shank 59 are laterally extending 110 inclined wings 62 normally urged in divergent relation by leaf or other springs 63, either of which is adapted to be engaged with the pawl 57.

Assuming that a submarine equipped with 115 my device sinks, or that it is unable to rise after having submerged in the usual manner, when the crew discovers the danger it is intended that the two manual levers 30 be swung to release the catches 38 associated therewith from engagement with the rim 24 of the float. A pull is then applied to the common cable 36 whereupon both cables 32 will be pulled and will swing the lever 31, thereby turning the associated 120 catches 28 out of engagement with the rim of the float. As there is nothing then to prevent, the float will naturally rise until it reaches the surface of the water, the cable 21 unwinding from the reel 20 and the 125 130

conductor 49 for the radio apparatus unwinding from the reel 50. When the float reaches the surface the pull upon the flexible members 21 is relieved and they remain locked within the grooves of the guide rollers. When the hooks 28 are released, it is apparent that the hook 44 will move out of engagement with the free end of the smallest section 41 of the aerial mast which is intended to serve as an antenna, and the spring 45 operates to swing this mast or aerial into vertical position, as clearly shown in Figure 5. The radio transmitting apparatus is controlled by means of current fed through the conductor 49 from any suitable source within the ship.

Assuming that a rescuing ship has been attracted by the signals and has arrived, it is intended that the crew of this ship B pull upon the float or floats, two or more being generally provided for each submarine, until the floats are immediately over the sunken vessel, after which the floats are disconnected from the cables 21. The connection of the bight portion of the cable with the reel 20 is such that when a hard pull is applied to the cable, this connection will be disengaged so that the cable will be disposed only about the roller 17. Assuming that the rescuing ship B has disconnected the floats, a suitable length of chain carrying the grapple shown in Figures 8 and 9 is attached to one end of the cable, while the other end thereof is brought onto a suitable windlass 35 or winch C which forms part of the equipment of the rescuing ship. When this windlass is turned, it is apparent that the cable 21 will be reeled in and that the grapple device will be lowered and guided to the roller 17, the grapple and the chain passing between the guide plate or grid 52 and the roller. Upon passing through this space the wings 62 of the grapple are compressed toward the shank thereof, the springs 63 being held of course under tension. When the grapple rides between the roller 17 and the pawl 55, the previously compressed wings will expand and engage at the end of the pawl, as shown in Figure 7. When such engagement has been made, it is apparent that the chains may be reeled in by the rescuing ship for lifting the sunken submarine. If desired, the grapples might be omitted and replaced simply by a suitable length of ordinary chain which may be threaded around the roller 17 and both ends then attached to a hoist or windlass for lifting the sunken ship.

In Figures 10 to 13, inclusive, I have shown my invention adapted for use in connection with surface vessels. In this instance I provide a plurality of carriers designated broadly by the numeral 64, which are located upon the deck or other convenient portion of the ship at spaced

points, as clearly shown in Figure 13. Each of these carriers includes a cage-like frame including uprights 65 connected at their upper ends by longitudinal and transverse strips 66 and 67, respectively, from the latter of which depend U-shaped supports 68 which have connected therewith saddle members 69 of curved shape. Each of these cages is designed to contain a float 70 formed with an elongated and preferably cylindrical hermetically sealed tank. The tank may be reinforced by any desired means, such as the ring 71. Illustrated and secured upon the sides thereof are brackets 72 with which are connected longitudinally extending hand-holes 73 designed to be grasped by survivors of a disaster so that they may support themselves in the water until help arrives. The ends of the tank carry eye bolts 74 for a purpose to be described.

Mounted beneath the cage structure is a base 75 equipped with suitable bearings within which is journaled a reel 76 on which is wrapped a cable or other flexible member 77, the cable being doubled and having its bight engaged upon a hook 78 arranged as shown in Figure 12, this hook arrangement being exactly the same as is provided on the reel 20. Also journaled in bearings on this base are grooved guide rollers 79 and 80 under which are trained the two stretches 82 of the cables. The roller 79 is relatively large and the arrangement of the rollers and the hook 78 is such that when the cable is entirely unwound from the reel 76 its bight will disengage the hook 78 and the cable will be engaged about the roller 79 alone in a manner which will be obvious. The ends of the cable are connected with the eye bolts 74 on the float.

Pivoted at 83 above the base 75 is a pawl 84 urged toward the roller 79 by a spring 85. This pawl is constructed in the same manner and is for the same purpose as the pawl 56 described in connection with the first form of the device.

Assuming that a ship equipped with the apparatus should sink it is of course apparent that the floats 70 will all rise out of their supporting cages 64 and will ascend to the surface of the body of water, as indicated in Figure 13, the cable 77 unreeling. The presence of these floats on the surface will indicate to other ships that there has been a leak and they will also serve to locate the sunken ship so that the proper steps may be taken to effect salvaging in the same manner as described in connection with the form of the device used on submarines, the same type of grapples being threaded onto the cables subsequent to the disconnection of the latter from the floats, the grapples being led down and engaged with the pawls 84 in exactly the same manner as they are engaged with the pawls 56 so that by means

of proper apparatus the submerged ship may be raised and salvaged.

From the foregoing description and a study of the drawings it will be apparent that I have thus provided a comparatively simple, inexpensive and easily installed apparatus which will be very convenient for the purpose specified and which on account of the fewness of the parts is not likely to be come deranged so that it should logically remain for a long time in proper condition for instant service whenever the exigencies of the occasion may demand.

While I have shown and described the preferred embodiments of my invention, it is of course to be understood that I reserve the right to make such changes in the form, construction and arrangement of parts as will not depart from the spirit of the invention or the scope of the subjoined claims.

I claim:

1. In an apparatus for raising sunken ships, an open topped chamber within the ship, a float mounted within said chamber, guide rollers within the chamber beneath the float, a windlass journally mounted within the chamber, a cable doubled and having its bight portion detachably connected with the windlass, the resultant stretches of the cable being wrapped about the windlass and trained under the guide rollers with the ends connected with the float, a plurality of rotatably mounted catch devices engaging the float for normally holding it within the chamber, and means connected with all of the catches and operable from a remote point whereby to effect release thereof simultaneously.

2. In an apparatus for raising sunken ships, an open topped chamber within the ship, a float mounted within said chamber, guide rollers within the chamber beneath the float, a windlass journally mounted within the chamber, a cable doubled and having its bight portion detachably connected with the windlass, the resultant stretches of the cable being wrapped about the windlass and trained under the guide rollers with the ends connected with the float, a plurality of rotatably mounted catch devices engaging the float for normally holding it within the chamber, and means connected with all of the catches and operable from a remote point whereby to effect release thereof simultaneously, said means comprising crank arms on the catches and flexible members connected with the crank arms, trained over guides, and connected with a common actuating element within the ship.

3. An apparatus for recovering sunken ships, comprising a float, means for mounting the float upon a ship, a reel journally mounted and carrying a cable secured to and wound thereon, guide rollers adjacent the reel under which the cable is passed, the free

ends of the cable being secured to the float, the cable being doubled and having its bight portion detachably engaged upon the reel whereby to automatically release from the reel and engage about one of said guide rollers when the cable is totally unwound, and a pivoted pawl adjacent the last named roller adapted to be engaged by a grapple engaged with an end of the cable subsequent to its disconnection from the float.

4. An apparatus for recovering sunken ships, comprising a float, means for mounting the float upon a ship, a reel journally mounted and carrying a cable secured to and wound thereon, guide rollers adjacent the reel under which the cable is passed, the free ends of the cable being secured to the float, and a pivoted catch device adjacent one roller in combination with a grapple adapted to be connected with one end of the cable subsequent to its disconnection from the float, the grapple being adapted to engage said catch.

5. In an apparatus of the character described, a chamber in the hull of a ship, a float within the chamber, a windlass in the chamber, a flexible member secured to and wrapped about the windlass and connected with the float, a normally telescoped aerial mast pivoted upon the float, means normally tending to swing the mast into upright position, and simultaneously releasable catch means for holding the float within the chamber and holding the mast in horizontal inoperative position upon the float.

6. In an apparatus of the character described, a float, a flexible member connected with the float, a windlass mechanism carrying the flexible member, an aerial mast pivoted upon the float, means normally tending to swing the mast into upright position, a reel, a conductor secured to and wrapped about the reel and connected with the mast, and a plurality of catch devices for holding the float upon the ship, one catch device having a portion engaging the mast and normally holding the same in horizontal inoperative position upon the float.

7. In a device of the character described, a float, a windlass mounted on the ship, a flexible member secured to and wrapped about the windlass and connected with the float, a telescopic mast pivoted upon the float, means tending to swing the mast into vertical position, means tending to extend the telescopic mast, and a plurality of catch devices engaging the float for holding the same upon the ship, one catch device having a hook-like extension engaging over the end of the mast in abutting relation thereto whereby to hold the mast in horizontal inactive position and to maintain it in telescoped position.

8. In a ship salvaging apparatus, a float, a flexible member connected with the float

and with the ship, a plurality of upright rotatable rods having lateral members normally engaging the edges of the float, said rods carrying crank arms, an actuating member extending into the hull of the ship, and flexible members connected with said actuating member and with said arms whereby all of said rods may be turned simultaneously to effect release of the float.

10 9. In a ship salvaging device, a float mounted within the hull of a ship and adapted to be released from within the hull, a main guide roller, a windlass, a flexible member doubled intermediate its ends and detachably engaged and wrapped about the windlass, the resultant stretches of the cable being disposed at opposite sides of said guide roller with the ends connected with the float, a guard member located beneath the guide roller in spaced relation thereto and having a guide extension terminating adjacent the windlass, the guard having an opening therein, a catch device pivoted beneath the guard and having one end spring-pressed through the opening, in combination with a grapple designed to be connected with the cable subsequent to disconnection

thereof from the float whereby the grapple may be drawn under said guide roller and engaged with said end of the catch device. 30

10. In an apparatus of the character described, a chamber built into the hull of a ship, a float seating within and normally closing the chamber, signaling means carried by the float, a reel journaled within the chamber and carrying a hook, a pair of spaced guide rollers, a cable doubled and wrapped upon the reel with its bight engaged upon the hook, the two stretches of the cable being engaged under said rollers and connected with the float, catch means adjacent one roller adapted to be engaged by a grapple led thereto by the cable, and means for securing the float within the chamber including rotatably mounted catches engaging the upper edge of the float, hand levers connected with certain of said catches, arms on the other of said catches, and flexible members connected with said arms, trained over guide pulleys 40 45 50 and brought into the ship.

In testimony whereof I affix my signature.

LEOPOLDO FIORILLO.
